UNITED STATES PATENT OFFICE

92,536

DESIGN FOR A WAISTCOAT

Rudolf Hirschfeld, New York, N. Y.

Application April 24, 1934, Serial No. 51,499

Term of patent 7 years

To all whom it may concern:

Be it known that I, RUDOLF HIRSCHFELD, a citizen of the United States, residing at New York city, county of the Bronx, and State of New York, have invented a new, original, and ornamental Design for a Waistcoat, of which the following is a specification, reference being had to the accompanying drawing, forming part thereof.

I claim:

The ornamental design for a waistcoat substantially as shown.

RUDOLF HIRSCHFELD.
